Attorney.

UNITED STATES PATENT OFFICE.

PEARL C. COLONY, OF LOS ANGELES, CALIFORNIA.

ADVERTISING-CAR CONSTRUCTION.

1,347,012.

Specification of Letters Patent.

Patented July 20, 1920.

Application filed July 15, 1919. Serial No. 310,997.

To all whom it may concern:

Be it known that I, PEARL C. COLONY, a citizen of the United States, residing at Los Angeles, in the county of Los Angeles and 5 State of California, have invented new and useful Improvements in Advertising-Car Constructions, of which the following is a specification.

The object of the present invention is to 10 provide a novel and effective means whereby the exterior of a piece of railway rolling stock or other vehicle can be utilized for advertising purposes, thereby increasing the revenues of the operating company and also 15 opening up a new field of advertising.

A further object of the invention is to provide an advertising device of this character which can be embodied directly in the construction of a car or vehicle, which will 20 effectively display advertising matter during the day and also during the night, which enables the advertising matter to be quickly changed as may become necessary, and which will not detract from the appearance of the 25 car or result in any unsightly projecting portions or attachments.

With these and other objects in view the invention consists in certain arrangements and combinations of the parts, as will more 30 fully appear as the description proceeds, the novel features thereof being pointed out in the appended claims.

For a full understanding of the invention reference is to be had to the following description and accompanying drawing, in 35 which:

Figure 1 is a side elevation of a portion of a street railway car which is provided with advertising means constructed in accordance with the invention;

Fig. 2 is a transverse vertical sectional view through one of the side walls of the closed portion of the car, taken on the line 2-2 of Fig. 1;

Fig. 3 is a horizontal sectional view on the line 3-3 of Fig. 2;

Fig. 4 is a vertical sectional view through one side of the open portion of the car, taken on the line 4-4, Fig. 1;

Corresponding and like parts are referred to in the following description and indicated in all the views of the drawing by like reference characters.

For the purpose of illustration the invention has been shown as embodied in a street railway car A which may be of the conven-

tional construction, said car having a closed portion 1 and an open portion 2. The side walls of the closed portion 1 are provided with open spaces 3 which are preferably 60 positioned just below the window sills 4, and which have transparencies 5 fitted across the open outer sides thereof. These open spaces 3 are arranged between the uprights 6 of the car frame and extend longitudinally of the car in a continuous series or row. The open portion 2 of the car has the usual grating 7 arranged between the uprights 6 and the sills 8, said grating being carried by the frames 9, and being cut away 70 to receive the boxes or casings 10. As in the previous instance transparencies 5 are fitted across the open outer sides of these casings.

As indicated by Fig. 2, the back of the open space is closed by a sheathing 11 which 75 constitutes the inner wall of the closed portion 1 of the car, while the outer side of the open space is closed by a glass plate 12 which is fitted within a frame 13. In the construction which has been illustrated these frames 80 13 are arranged between the upper and lower longitudinally extending beads 14 which project outwardly from the side of the car, the upper bead or rim being just below the window sills 4, while the lower bead is disposed 85 at an intermediate point between the window sills and the bottom 15 of the car. Each frame 13 is shown as hinged at its upper edge to the upper bead 14, as indicated at 16, thereby enabling it to be swung outwardly when it is necessary to clean the glass plate 12 or obtain access to the interior of the space or chamber 3. When the frame 13 is 90 swung downwardly the space or chamber 3 is closed, and the glass plate is flush with the outer sides of the car so that there are no 95 exterior projections such as would detract from the appearance of the car or cause trouble by coming into engagement with exterior objects. These transparent doors, as 100 they may be termed, may be fastened in a closed position in any suitable manner. In the present instance a retaining strip 17 is shown as arranged between each pair of the frames 13, the lower end of the retaining 105 strip being hinged at 18 to the lower bead 14, while the upper end thereof is formed with a latch 19 which is adapted to engage the upper bead 14. Each retaining strip may have a T-shaped cross section and be formed 110 with a flange 17a which is received between the adjacent frames 13, as indicated more

clearly by Fig. 3. This will tend to hold the parts securely in proper position and prevent looseness or play. The transparent panels or doors are thus locked securely in a closed position when the car is in operation, although they can be readily unlocked and swung outwardly at any time when it may be necessary to clean the glass plate or replace a broken one.

10 The transparency 5, which may have any suitable characters or advertising matter, such as that indicated at 20, provided thereon, is arranged within the chamber 3 just back of the glass plate 12. In the preferred 15 construction this transparency 5 is slidably received within channeled guides provided at the sides of the open space, and is removable through the top thereof, thereby enabling the transparencies to be removed 20 and changed as often as may be desired and without any difficulty. For this purpose a swinging closure 22 is provided at the top of the chamber 3, said closure constituting the forward edge of the window sill 4, and 25 being hingedly connected thereto at 23. When this closure is swung upwardly, as indicated by Fig. 2, the transparency can be readily lifted out of position. A suitable source of light, such as the incandescent 30 lamps 24, is provided within each chamber 3, so that the transparencies can be illuminated at night, although during the day the transparencies will be visible without the necessity of using artificial light. For the 35 purpose of diffusing the light from the lamps 24 a bright sheet or reflecting surface 25 may be applied to the rear wall of each of the chambers 3. This will be of assistance in obtaining a uniform illumination of 40 the transparencies.

The open outer sides of the casings 10 are closed by glass plates 12 which are fitted within the frames 13 and mounted upon the car exactly as in the previous instance. All 45 of the glass plates 12 throughout the entire length of the car, including both the closed portion 1 thereof and the open portion 2 thereof, are uniform in size and position, so that a continuous series of advertising trans- 50 parencies can be displayed at the side of the car. As previously explained, the casings 10 are fitted within the frames 9 which carry the gratings 7, and the transparencies 5 are slidably received within channeled guides 21 55 which are applied to the end portions of the casings at the front thereof. The transparencies 5 are thus positioned back of the glass plates 12, and hinged closures 26 at the top of the casings 10 enable the trans- 60 parencies to be removed and changed without difficulty. In the present instance these hinged closures 26 are shown as applied to the outer edge portions of the sills 8. A reflecting sheet 27 may be applied to the 65 back of each of the casings 10 for the pur-

pose of diffusing the light from the incandescent lamps 24 and obtaining an even illumination of the transparencies. A most effective means of advertising is provided by this invention, and the building of railway rolling stock in this manner will provide for an increase in the revenues of any railway company and also open up a field of advertising which has hitherto been overlooked.

Having thus disclosed my invention, I claim and desire to secure by Letters Patent:

1. A car formed with the usual side wall including spaced uprights, windows being provided between the upper portions of the 80 uprights and outer and inner sheathing being applied to the lower portions of the uprights, the wall being formed with a longitudinally extending series of outwardly facing hollow chambers arranged under the 85 windows and between the uprights, transparencies at the outer sides of the chambers, and means within the chambers for illuminating the transparencies.

2. A car formed with the usual side 90 frame including spaced uprights having windows between the upper portions thereof, outer and inner sheathing being applied to the lower portions of the uprights and a longitudinally extending series of out- 95 wardly opening chambers being built in the side wall between the uprights and under the windows, said hollow chambers being uniform in size and shape and arranged in longitudinal alignment, removable trans- 100 parencies arranged interchangeably at the outer sides of the chambers, and means within the chambers for illuminating the transparencies.

3. A car formed with the usual side frame 105 including spaced uprights having windows between the upper portions thereof, outer and inner sheathing being applied to the lower portion of the uprights and outwardly facing hollow chambers being built 110 into the side wall between the uprights and below the windows, removable transparencies arranged at the outer sides of the hollow chambers, said transparencies being interchangeable and being movable vertically into and out of operative position from the window openings, and means within the chambers for illuminating the transparencies.

4. A car provided with the usual windows and window sills and also with spaced longitudinally extending beads projecting from the exterior thereof below the window sills, said car being provided with outwardly facing hollow chambers which are 120 built in the side walls thereof at points below the window sills and between the beads, removable and interchangeable transparencies at the outer sides of the hollow chambers, and means within the hollow 125 130

chambers for illuminating the transparencies.

5. A car having an outwardly facing chamber built in the side walls thereof, a 5 glass door arranged substantially flush with the outer face of the car and closing the chamber, said glass door being hingedly connected to the car at one side of the chamber, retaining strips applied to the car and 10 engaging opposite ends of the glass door to lock the door in a closed position, a transparency fitted in the chamber back of the glass door, and a source of light arranged within the chamber for illuminating the transparency. 15

6. A car having an outwardly facing chamber built in the side walls thereof, a glass door arranged substantially flush with the exterior of the car and hingedly connected to the car at one side of the chamber, retaining strips hingedly connected to the car at the opposite side of the chamber and adapted to be swung into position over the ends of the door to lock the door in 20 a closed position, a transparency arranged within the chamber back of the glass door, and a source of light arranged within the chamber to illuminate the transparency. 25

7. A car provided with the usual windows and window sills and also with spaced longitudinally extending beads projecting from the exterior thereof below the window sills, said car being provided with outwardly facing hollow chambers which are built in 30 the side walls thereof at points below the window sills and between the beads, movable closures associated with the window 35

sills and arranged at the top of the chambers, glass doors closing the outer sides of the chambers and arranged between the 40 longitudinally extending beads of the car and substantially flush with the outer face of the car, guide channels at the ends of the chambers, removable transparencies fitted slidably within the guide channels 45 and adapted to be inserted in position or removed through the openings at the top of the chambers controlled by the closures, and a source of light within each chamber for illuminating the respective transparency. 50

8. A car formed with the usual frame including spaced uprights connected at an intermediate point between the floor and top by substantially horizontally extending sills, a casing arranged under each of the 55 sills and extending between the adjacent uprights, a closure for the top of each casing associated with the respective sill, a glass door closing each of the casings and arranged substantially flush with the exterior of the 60 car, guide channels at the ends of each casing, a transparency fitted slidably within the guide channels of each casing and removable through the opening controlled by the closure at the top of the casing, and a 65 source of light within each casing for illuminating the respective transparency.

In testimony whereof, I have signed my name to this specification in the presence of two subscribing witnesses.

PEARL C. COLONY.
